UNITED STATES PATENT OFFICE.

WILLIAM H. BOOTH, OF SANTA CRUZ, CALIFORNIA.

DRAIN-TILE.

No. 914,231.

Specification of Letters Patent.

Patented March 2, 1909.

Application filed September 9, 1908. Serial No. 452,188.

To all whom it may concern:

Be it known that I, WILLIAM H. BOOTH, a citizen of the United States, residing at Santa Cruz, in the county of Santa Cruz and State 5 of California, have invented new and useful Improvements in Drain-Tiles, of which the following is a specification.

This invention relates to drain tiles and one of the principal objects of the same is to 10 provide a drain tile for forming gutters at the opposite sides of streets or roads, said tile having oppositely disposed inclined flanges to direct the water to the tile, and said tile being provided with perforations at suitable 15 intervals to permit the water to pass into the tile and to prevent large particles of foreign matter from entering the tile.

Another object of the invention is to provide a tile joint in which a cap is formed at 20 one end to receive the end of one of the pipe sections of the drain tile.

Still another object of the invention is to provide a drain tile of two sections divided longitudinally, the lower section having inclined flanges to direct the water to the tile and the upper section of said tile being perforated at its base and fitted to the lower section to exclude large particles from the tile.

These and other objects may be attained 30 by means of the construction illustrated in the accompanying drawing in which:

Figure 1 is a perspective view of a drain tile section made in accordance with my invention. Fig. 2 is an end view of the same. 35 Fig. 3 is a longitudinal section.

Referring to the drawing the numeral 1 designates the lower section of the drain tile which is substantially semicircular in cross section and provided at one side with a curb 40 flange 2 and at the opposite side with an inclined gutter flange 3, said flanges being of any suitable width, depending upon the required area of the gutter. Formed upon one end of the base member 1 is an offset semicircular flange 4 provided with an outwardly extending ledge or support 5 at one side and a shorter supporting ledge 6 at the opposite side, said ledge conforming to the inclinations

of the flanges 2 and 3 and being offset from said flanges to form supporting ledges for the 50 flanges on the next adjacent section of the tile. The flanges 2 and 3 are each provided with a recess 7 for a purpose which will presently appear.

The upper section of the tile comprises the 55 member 8 which in cross section forms a complete circle with the lower section 1. The section 8 at its lower edges is provided with suitable perforations 9 which will permit the water to flow from the flanges into 60 the drain tile. One end of the section 8 is provided with a cap or flange 10 which forms a continuation of the flange 4 of section 1, said cap or flange 10 being fitted into the recess 7 in the ends of the flanges 2 and 3. 65 Recesses 11 are also formed in the flanges 2 and 3 at their opposite ends to accommodate the flange 4 and cap 10 on an adjacent section of the tile.

From the foregoing it will be obvious that 70 a drain tile made in accordance with my invention may be quickly laid, that the sections may be readily connected by placing the smaller ends of the tile in the cap or flange and uniting the same by cement. It 75 will also be apparent that the sections are all supported with the flanges 2 and 3 at substantially the same inclination; thus providing a combined gutter and drain tile.

I claim:

1. A drain tile comprising sections each composed of an upper and a lower member, one superposed upon the other, the lower section being provided with oppositely inclined flanges and the upper section having 85 at its lower edges perforations communicating with the interior of the tile.

2. A drain tile composed of upper and lower sections divided longitudinally, the lower section comprising a semicircular member, and oppositely inclined flanges and an offset at one end, said flanges being provided with recesses, and an upper section fitted to the lower section and provided with perforations which communicate with the 95 interior of the tile, said upper section being

80

95

provided with a cap or flange which forms a continuation of the flange of the lower section.

3. A drain tile comprising upper and lower sections divided longitudinally, the lower section having oppositely disposed flanges and offset ledges, said flanges being provided with recesses and an upper section provided with perforations which communicate with

the interior of the tile, and an end cap fitted 10 into the recesses in the flanges of the lower section.

In testimony whereof I affix my signature in presence of two witnesses.

WILLIAM H. BOOTH.

Witnesses:

B. J. BLAISDELL,
A. W. WYMAN.
